UNITED STATES PATENT OFFICE.

CHARLES ALGERNON PARSONS AND FRANCIS WILLIAM GARDNER, OF NEWCASTLE-ON-TYNE, ENGLAND; SAID GARDNER ASSIGNOR TO SAID PARSONS.

TURBINE BLADING.

Application filed May 24, 1924. Serial No. 715,638.

To all whom it may concern:

Be it known that we, CHARLES ALGERNON PARSONS and FRANCIS WILLIAM GARDNER, both subjects of the King of Great Britain and Ireland, and both residing at Heaton Works, Newcastle-on-Tyne, in the county of Northumberland, England, have invented certain new and useful Improvements in and Relating to Turbine Blading, of which the following is a specification.

This invention relates to the blading of turbines.

It is customary in turbines of the reaction type for the blades in the fixed and moving rows to be of the same dimensions and to be spaced apart by means of suitable distance pieces so that the fluid passage through the rotor blades corresponds at all radial distances with the fluid passage through the stator blades.

Further, the fixed and moving blades are sometimes twisted about their longitudinal axes so that cross-sections of the blade taken at different radial distances make different angles with the longitudinal axis of the rotor for the purpose of obtaining a more uniform opening along the blade or for the purpose of varying the angle of the fluid discharge along the length of the blade to suit the varying circumferential speed. In such cases also the steam passage can be made to correspond in adjacent fixed and moving rows at all corresponding radial positions.

In some cases, however, it is found expedient to make the rotor blades taper in thickness from the root to the tip in order to decrease the stress at the root caused by centrifugal force. In such a case the correspondence between the adjacent fixed and moving blades no longer exists, so that in non-twisted blades the fluid passage through the fixed blades cannot be made the same as that through the moving blades at all corresponding radial distances, the result being a difference in the velocity of the steam relatively to the blades in the case of the blades of the rotor and stator respectively, and also a lateral displacement of the fluid in passing between the adjacent fixed and moving rows with a consequent loss of efficiency.

In the case of the twisted blades, tapering of the rotor blades causes a similar

lack of correspondence in the fluid passages. If in such a case the amount of twist of either stator or rotor blades is increased or decreased so as to make the discharge opening of the fluid passages equal at corresponding points, a further difficulty is encountered, namely, the angle of discharge of the fluid no longer corresponds at all radial points to the circumferential velocity of the blades.

The object of the present invention is to overcome these difficulties.

With such an object the invention consists in the improvements in turbine blading hereinafter described and particularly pointed out in the claims.

Referring to the accompanying drawings which are to a certain extent of a diagrammatic nature:

Figure 1 shows a sectional elevation through part of an axial-flow reaction turbine;

Figures 2^a, 3^a and 4^a being cross-sections through adjacent blades taken respectively on the lines 2—2, 3—3 and 4—4 of Figure 1 to show the taper of the blades, and

Figure 5 a corresponding sectional perspective view of one of the stator blades;

Figures 2^b, 3^b and 4^b are cross-sections also taken respectively on the lines 2—2, 3—3 and 4—4 of Figure 1 of a modification in which the tapered blades are also twisted;

Figure 6 being a corresponding sectional perspective view of one of the stator blades, finally

Figure 7 shows a sectional elevation through part of an axial-flow reaction turbine, in which the stator and rotor blades are of different widths, while

Figures 8, 9 and 10 are cross-sections respectively on the lines 8—8, 9—9 and 10—10 of Figure 7.

In each of the Figures 2^a, 3^a and 4^a, 2^b, 3^b and 4^b and 8, 9 and 10, the stator blades are shown above and the rotor blades below, while the same reference letters are used throughout to denote corresponding parts in the different figures.

In carrying the invention into effect according to one form as shown in Figures 1, 2^a, 3^a, 4^a and 5 applied to an axial-flow reaction turbine, the spaced rotor blades, *a*, are secured in any suitable manner to the

rotor, b , and as shown by the cross-section in Figures 2^a, 3^a and 4^a decrease in thickness from root, a' , to tip, a^2 , in order to lessen the stress due to centrifugal force. 5 Similarly, the stator blades, c , spaced to correspond are suitably secured to the stator body, d , but as shown in Figures 2^a, 3^a and 4^a, decrease in thickness from tip c^2 , to root, c' , their thickness being equal to that of 10 the rotor blades at equal radial distances. In Figure 5, a perspective view of such a stator blade is shown decreasing in thickness from the tip, c^2 , to the root end, c' , where it joins the root, e , itself. By so proportioning and arranging the stator and rotor blades, it will be seen that the thick tips, c^2 , of the stator blades coact with the thick roots, a' , of the rotor blades and the thin roots, c' , of the stator blades with the thin 15 tips, a^2 , of the rotor blades, so that the fluid passage through the stator blades corresponds at all radial distances with the fluid passage through the rotor blades.

According to a modified form of the invention, the stator and rotor blades as regards thickness and relative arrangement are as above described but in addition, as shown in Figures 2^b, 3^b, and 4^b, are twisted about their longitudinal axes so as to make 20 the angle of discharge of the fluid correspond at all radial distances to the circumferential velocity of the blades. As the section of the stator blades at any radial distance is the same as the section of the 25 rotor blades at the same distance, the twisting of the blades will not alter the corresponding steam passages between the rotor and the stator blades, and thus no loss in efficiency will be incurred.

40 In Figure 6, a perspective view of such a twisted stator blade is shown, the thick tip being indicated at c^2 and the thin root end at c' .

Further, in some cases, either to meet special stress conditions or for some other reason, it is convenient to adopt a stator blade of different width from the rotor blade. Thus, as shown in Figures 7 to 10, the stator blade, f , is of less width than the rotor 45 blade, a , but decreases as before from the maximum thickness at the tip, f^2 , to a minimum thickness at the root, f' . The rotor blades, as before, decrease in thickness from the root, a' , to the tip, a^2 . In this case, 50 as seen in Figures 8 to 10, the stator blades, f , are more closely spaced than the rotor blades, a , so that the passages, h , for steam flow between the stator blades may be geometrically similar, or approximately geometrically similar, to the passages, i , between the rotor blades.

The rotor and stator blades may be provided in the first place with the required taper or they may be tapered by any suit-

able means from blades of parallel section 65 produced by any known method.

Having now described our invention, what we claim as new and desire to secure by Letters Patent is:—

1. In combination in a turbine, relatively 70 rotatable co-axial blade-carrying elements, outwardly-projecting blades decreasing in thickness from root to tip carried by one of said elements, and co-acting therewith inwardly-projecting blades decreasing in 75 thickness from tip to root carried by the other of said elements, as set forth.

2. In combination in a turbine, co-axial 80 stator and rotor elements and co-acting blades carried by said elements, said blades carried by said rotor element decreasing in thickness from root to tip and said blades carried by said stator element decreasing in thickness from tip to root, as set forth.

3. In combination in a turbine, relatively 85 rotatable co-axial blade-carrying elements; outwardly-projecting blades twisted about their longitudinal axes carried by one of said elements, and co-acting therewith inwardly-projecting blades twisted about their 90 longitudinal axes carried by the other of said elements, said outwardly-projecting blades decreasing in thickness from root to tip and said inwardly-projecting blades decreasing in thickness from tip to root, as 95 set forth.

4. In combination in a turbine, relatively 100 rotatable co-axial blade-carrying elements; outwardly-projecting blades decreasing in thickness from root to tip carried by one of said elements, and co-acting therewith inwardly-projecting blades decreasing in thickness from tip to root carried by the other of said elements, said outwardly-projecting 105 and said inwardly-projecting blades having the same thickness at equal distances from the axis, as set forth.

5. In combination in a turbine, relatively 110 rotatable co-axial blade-carrying elements; outwardly-projecting blades decreasing in thickness from root to tip carried by one of said elements, and co-acting therewith inwardly-projecting blades decreasing in thickness from tip to root carried by the 115 other of said elements, said outwardly-projecting and said inwardly-projecting blades decreasing in thickness at the same rate, as set forth.

6. A turbine stator blade thicker at the 120 tip than at the root, as set forth.

7. A turbine stator blade thicker at the tip than at the root and twisted about its longitudinal axis, as set forth.

In testimony whereof we have signed our 125 names to this specification.

CHARLES ALGERNON PARSONS.
FRANCIS WILLIAM GARDNER.
